UNITED STATES PATENT OFFICE.

PHILIP MUELLER, OF DECATUR, ILLINOIS.

BUBBLER-HEAD FOR SANITARY DRINKING-FOUNTAINS.

1,248,377.

Specification of Letters Patent. Patented Nov. 27, 1917.

Application filed January 3, 1917. Serial No. 140,383.

To all whom it may concern:

Be it known that I, PHILIP MUELLER, a citizen of the United States, residing at Decatur, in the county of Macon and State of Illinois, have invented new and useful Improvements in Bubbler-Heads for Sanitary Drinking-Fountains, of which the following is a specification.

The present invention relates to sanitary drinking fountains, and particularly to that type in which a drinking bubble is projected above the surface of the delivery nozzle, which drinking bubble may be continuous, or may be intermittent and controlled by a suitable valve which will be turned on by the user.

My invention relates particularly to the nozzles or bubbler head regardless of the other accessories of the fountain.

One of the objects of my invention is to provide a nozzle which may be constructed principally of metal, for convenience and cheapness in manufacture and assembling, but in which porcelain or other suitable vitreous material is utilized to form the exposed and jet discharging element of the nozzle, so that the attractive appearance and sanitary properties of the porcelain head are secured without the expense and difficulties incident to molding the entire nozzle or bubbler head of vitreous material.

Another object of the invention is to provide a bubbler head which is entirely sanitary, and in which failure of the bubble, by reason of clogging of the discharge orifices in the head, cannot take place, and in which, furthermore, the matter of clearing any of the discharge orifices which may become clogged by foreign matter is easily accomplished.

In order that the invention may be clear to those skilled in the art, I have shown herein one embodiment of the invention, but it will be understood that the construction may be varied within the range of mechanical skill from the specific disclosure here made without departing from the spirit of my invention.

In the drawings:

Figure 1 is a view in side elevation of a supply pipe, stand pipe, and bubbler head, disclosing my invention.

Fig. 2 is a view in vertical cross section of the bubbler head.

Fig. 3 is a plan view of the bubbler head.

Referring to the drawings by numbers, like numbers indicating like parts in the several views, 10 indicates any suitable supply pipe, and 11 any suitable stand pipe, the stand pipe in the present instance being shown as provided with a suitable valve which may be of the self-closing type, and which controls flow to the bubbler head.

Mounted on said stand pipe is the bubbler head 12 composed of the metal body portion 13, which is enlarged or flared from the stand pipe connection upwardly, so as to give a chamber of considerable capacity, in which chamber, if desired, may be mounted any regulating means to cut down the volume to be delivered, if such regulating means is necessary. The regulating means is not shown, as it may take various forms, and I do not confine myself to any particular type, if such regulation is found necessary.

The enlarged chamber of the body portion 13 is screw-threaded, preferably on its interior to receive a metal ring 14, said metal ring engaging at its upper end a seat 15 formed in a porcelain cover plate 16, the said ring and plate being secured together, preferably by cement, as indicated at 17, so as to form substantially an integral structure. It will be observed that the metal ring 15 is of smaller diameter than the porcelain cover plate 16, so that when the ring 14 is screwed into the body portion the porcelain cover plate will rest upon the top of the body portion and make a close and finished joint therewith.

The cover plate 16 of porcelain is, in the present embodiment, shown as substantially flat, having the depending rim in which the seat 15 is formed, this depending rim extending downwardly a short distance so as to give an attractive appearance, and a completely sanitary vitreous top.

By forming the cover plate 16 in the manner shown, and assembling it with the metal ring 14 as described, a construction is provided which may be very readily secured to the body portion 13, and in event of breakage of the porcelain cover plate the same may be replaced without disturbing the body portion proper, either by substituting a new cover plate and metal ring, or by cementing a new cover plate to said ring. By providing the porcelain cover plate with the short depending rim, a vitre-

ous surface is provided of sufficient area to give an entirely sanitary nozzle without the necessity of forming the entire nozzle of porcelain, and, furthermore, one in which the 5 surface will not corrode or discolor in use.

The cover plate 16 is provided with discharge or jet-forming orifices 18, circularly disposed about the axis of the cover plate, and these orifices 18 are so placed as to deliver converging jets to the center of the bubbler head, so that the meeting streams will form a bubble or geyser, which will be projected a considerable distance above the head. In the particular embodiment shown 10 the orifices 18 are inclined to bring about this meeting of the jets, but it will be understood that I do not limit myself to the particular inclination or direction of the jets here disclosed.

20 It will be observed that the jet orifices 18 are arranged in a plurality of radially disposed series, so that there will be projected a plurality of streams toward the center as distinguished from that type of fountain 25 now in use, in which a single circularly disposed row of jets or nozzles are provided which meet at the center and form a bubble. The advantage of a plurality of jets directed substantially to a common central point over 30 that type of fountain in which a single circular row of jets deliver to a central point, is that if, for any reason, one of the radially disposed jets is stopped by reason of clogging of the discharge orifice, the drinking fountain will not be destroyed, for the other 35 jet or jets will preserve that bubble and prevent spraying of the water to one side, which always occurs in the type of fountain to which I have referred, if for any 40 reason one of the single circle of jets is stopped.

The advantage of this plurality of radially disposed jets all delivering to the center is that not only will the drinking 45 bubble be preserved though one or more of the discharge orifices be clogged, but danger of discharging water from the fountain and onto the floor is eliminated.

It will be understood that such changes as 50 are merely mechanical expedients, and substitution of equivalent elements for those herein disclosed, are to be regarded as within the range of my invention.

I claim:

55 1. A nozzle for drinking fountains comprising a metal body portion having a supply-pipe connection and a relatively large open-topped water-receiving chamber, a perforated cover-plate of vitreous material for said chamber having a depending rim, and metal securing means carried on the inner edge of the depending rim of said cover plate and adapted to engage said body portion.

65 2. A nozzle for drinking fountains com-

prising a metal body portion having a supply-pipe connection and a relatively large open-topped water-receiving chamber, a perforated cover plate of vitreous material for said chamber having a depending rim, and a metal ring secured to the inner surface of the depending rim of said cover-plate and adapted to engage said body portion. 70

3. A nozzle for drinking fountains comprising a metal body portion having a supply-pipe connection and a relatively large open-topped water-receiving chamber, a perforated cover-plate of vitreous material for said chamber having a depending rim, and a screw-threaded metal ring depending from the inner surface of the depending rim of said cover-plate and adapted to engage said body-portion. 75

4. A nozzle for drinking fountains comprising a metal body portion having a supply-pipe connection and a relatively large open-topped water-receiving chamber, a perforated cover-plate of vitreous material for said chamber having a depending rim, and a metal ring secured in an annular seat 85 formed in said cover-plate and adapted to engage said body portion, said ring being inset from the periphery of said cover-plate to permit the vitreous plate to seat snugly on the upper edge of said body portion. 90

5. A cover-plate for drinking fountains formed of a vitreous shell with a perforated upper face and a depending rim having an annular seat formed therein, and a metal ring fixed in said seat and provided with 100 means for securing said cover-plate to a fountain. 95

6. A cover-plate for drinking fountains formed of a vitreous shell with a perforated upper face and a depending rim having an annular seat formed in its edge interiorly of the rim, and a metal ring fixed in said seat, said ring being of smaller diameter than said rim to provide an offset and having means to engage and secure said cover-plate 110 to a fountain. 105

7. A bubbler-head for drinking fountains having a plurality of discharge orifices arranged in rows and opposed series so as to deliver a plurality of meeting streams to 115 form a central bubble.

8. A bubbler-head for drinking fountains having a plurality of discharge orifices arranged in substantially diametrically opposed radial rows so as to deliver a plurality of streams to 120 form a central bubble.

9. A bubbler-head for drinking fountains having a plurality of substantially radially disposed discharge orifices arranged in substantially diametrically opposed radial rows so as to deliver a plurality of streams to 125 form a central bubble.

10. A bubbler-head for drinking fountains having a plurality of discharge orifices arranged circularly in substantially di- 130

ametrically opposed substantially radial rows so as to deliver a plurality of streams to form a central bubble.

11. A bubbler-head for drinking fountains having a plurality of substantially diametrically opposed substantially radial rows of discharge orifices circularly arranged and so inclined as to deliver a plurality of converging streams to form a central bubble.

12. A bubbler-head for drinking fountains having a plurality of diametrically opposed radial rows of discharge orifices circularly arranged and so inclined as to deliver a plurality of substantially parallel streams to form a central bubble.

13. A bubbler-head for drinking fountains having a plurality of rows of discharge orifices about the vertical axis of the head, the orifices of each row delivering to a common point to form a central bubble.

14. A bubbler-head for drinking fountains having a plurality of rows of discharge orifices circularly disposed about the vertical axis of the head, the orifices of each row delivering to a common point to form a central bubble.

15. A bubbler head for drinking fountains having a plurality of opposed rows of discharge orifices to deliver a plurality of

streams to form a central bubble, the orifices in each row being of unequal distance from the central bubble.

16. A bubbler head for drinking fountains having a plurality of substantially diametrically opposed rows of discharge orifices to deliver a plurality of streams to form a central bubble, the orifices in each row being of unequal distance from the central bubble.

17. A bubbler head for drinking fountains having a plurality of opposed rows of discharge orifices circularly arranged to deliver a plurality of streams to form a central bubble, the orifices in each row being of unequal distance from the central bubble.

18. A bubbler head for drinking fountains having a plurality of substantially diametrically opposed rows of discharge orifices circularly arranged to deliver a plurality of streams to form a central bubble, the orifices in each row being of unequal distance from the central bubble.

In testimony whereof I have hereunto set my hand in presence of two subscribing witnesses.

PHILIP MUELLER.
